BILLIARD CUE

Jacques R. Blum, San Francisco, Calif.

Application December 26, 1940, Serial No. 371,731

4 Claims. (Cl. 273—68)

This invention relates to improvements in billiard cues, and more particularly to an improved handle and loading means therefor.

An object of my invention is to provide an improved cue grip formed of plastic material, secure in placement and ornamental in appearance.

Another object of my invention is to provide a cue grip of the kind characterized, which can be suitably colored by the addition of certain pigments to the plastic material, to match the wood of the cue or the color of surrounding furnishings.

A further object of my invention is to provide, in combination with a cue grip of the kind characterized, a loading member advantageously positioned to properly balance the cue and concealed from view and secured in place by the plastic material.

Other objects of my invention are to provide a device of the kind characterized which may be readily applied to the handle end of a cue of conventional construction, and which is ornamental in appearance, useful and efficient in performance, simple in structure and inexpensive to manufacture.

To the accomplishment of these and such other objects as may hereinafter appear, the invention consists of the novel construction and arrangement of parts herein specifically described and illustrated in the accompanying drawings wherein is shown an embodiment of the invention, but it is understood that the device shown is merely an illustration of what is now thought to be the preferred embodiment thereof, and that various changes in respect to the form, proportions and minor details of construction may be resorted to without departing from the principles of or sacrificing any of the advantages of the invention.

In the accompanying drawings:

Fig. 1 is a side elevation of a fragmentary part of the handle of a conventional billiard cue;

Fig. 2 shows the first step or operation in the production of a cue embodying my improved grip and loading member;

Fig. 3 is a side elevation of the said part of the cue handle showing the next (second) step or operation followed in the production of my invention;

Fig. 4 is a side elevation of the said part of the cue handle showing the third step or operation followed in the production of my invention;

Fig. 5 is a longitudinal sectional view of a cue handle embodying my invention in its completed form;

Fig. 6 is a sectional view taken on the line 6—6 of Fig. 5; and

Fig. 7 is a side elevation of the handle portion of a cue which embodies my invention in its completed form.

Referring particularly to Fig. 1, the numeral 10 designates the handle or butt of a conventional billiard cue, and as shown it is ordinarily symmetrically tapered.

As shown in Fig. 2 the first steps in developing my invention consist in cutting as by means of a lathe and cutting tool, an annular recessed portion 11, a substantially V-shaped annular groove 12 at each end of the recessed portion, and a still deeper annular under cut portion 13 between the ends of the recessed portion 11. As a result of the cutting away of the cue butt where the recessed portion 11 and the undercut portion 13 occur, there is provided a suitably shaped and proportioned core section. The undercut portion 13 is preferably of sufficient size and shape to accommodate a load member 14 of predetermined weight. In ordinary practice the positioning of the under cut portion 13 and the load member 14 are so prearranged with respect to the ends of the cue as to bring the latter into proper balance. The load member 14 preferably comprises a flat sheet of lead or other suitable material of the proper shape and thickness which is wrapped around that part of the wooden core section provided at the under cut portion 13 and then tacked in place, as shown in Fig. 3.

Fig. 4 illustrates the result of the succeeding step in the development of my invention which comprises the application of an oversized body or sleeve 15 of plastic material to and within the recessed portion 11. This is accomplished by preparing a mixture of plastic wood or other similar material, applying it to the recessed portion 11 and rolling it in place on a glass support which has been first treated with a coating of stearic acid or any other material capable of preventing the adherence of the plastic material to the glass support. When the plastic body 15 has been applied as aforesaid, it becomes lodged at its ends within the annular V-shaped grooves 12, while at the same time it extends around and engages with the outer surface of the load member 14, thereby securely holding the load member in place and preventing the displacement thereof when the plastic body 15 has solidified. After the application of the plastic material as aforesaid, the cue is preferably placed in a suitable holder until the said material has thoroughly solidified.

To complete the development of my invention, the cue is next mounted in a lathe and the over-

sized plastic body 15 is turned down to such an extent that its outer surface 16 is tapered and symmetrical with respect to the adjacent portions 17 and 18 of the cue handle, as shown in Figs. 5 and 7.

The mottled effect 19 illustrated on Fig. 7 can be obtained by mixing with the plastic material one or more suitable colored pigments. If the pigments are thoroughly mixed with the plastic material, the resultant cue grip will have a solid color throughout, but if the pigments are not thoroughly mixed with the plastic material, a mottled effect will result.

The plastic material may be applied by means of a mold instead of by the method above described, and in some instances a heated die may be employed to convert a powdered material into a plastic state or to produce certain burnished effects on the completed grip.

Having described my invention, what I claim is:

1. In combination with a billiard cue, a solid handle portion at one end of the cue having an annular recess formed therein, the said handle portion having a continuous core section where the recess occurs, a load member secured to the core section of the handle portion and positioned within the confines of the recess, and a plastic sleeve secured to the core section of the handle portion and positioned within the recess and extending over the load member.

2. In combination with a billiard cue, a handle portion at one end of the cue having an annular recess formed in the handle portion, the said handle portion having a continuous core section

where the recess occurs, a load member encircling the core section of the handle portion and positioned within the confines of the annular recess, and a plastic sleeve positioned within the annular recess and extending around and in engagement with the load member.

3. In combination with a billiard cue, a tapered handle portion at one end of the cue having an annular recess formed therein, the said handle portion having a continuous core section where the recess occurs, a load member secured to the core section of the handle portion and positioned within the confines of the annular recess, and a plastic sleeve extending around and in engagement with the core section and the load member and substantially filling the annular recess, the said sleeve having a tapered outer surface conforming to and being co-extensive with the tapered outer surface of the handle portion.

4. In combination with a billiard cue, a handle portion at one end of the cue having an annular recess formed therein, the said handle portion having a continuous core section where the recess occurs, a substantially V-shaped under cut annular groove formed in the handle portion at an end of the annular recess, a load member secured to the core section of the handle portion and positioned within the confines of the annular recess, and a plastic sleeve substantially filling the annular recess and the groove and extending over the load member, the said plastic sleeve being locked at one of its ends within the annular groove.

JACQUES R. BLUM.
